UNITED STATES PATENT OFFICE.

CLAUDE E. MENTZER, OF DES MOINES, IOWA, ASSIGNOR OF ONE-HALF TO CHRIST MAKRIS, OF DES MOINES, IOWA.

TOY AIRPLANE PROJECTILE GUN.

Application filed April 26, 1926. Serial No. 104,639.

The principal object of this invention is to provide a toy pistol having a rubber band for shooting a small airplane or the like into the air.

5 A further object is to provide a novel toy which is durable, economical in manufacture and instructive to the user.

A further object is to provide a novel means for holding the rubber band on the 10 gun and providing for its easy removal or replacement.

A still further object is to provide a rubber nose member on the airplane so that the same will not mar or damage objects it 15 might come in contact with.

These and other objects will be apparent to those skilled in the art.

My invention consists in the construction, arrangement and combination of the various 20 parts of the device, whereby the objects contemplated are attained as hereinafter more fully set forth, pointed out in my claims and illustrated in the accompanying drawings, in which:

25 Fig. 1 is a side view of my gun with a small airplane mounted thereon and ready to be shot into the air. Sections of the device are cut away to more fully illustrate the same.

30 Fig. 2 is a perspective view of the toy airplane to be shot into the air. This view shows the rubber nose and the trigger notch in the bottom of the plane to advantage.

35 Fig. 3 is a front sectional view of the complete device and is taken on line 3—3 of Fig. 1.

Fig. 4 is a top plan view of the end of the gun barrel and shows the means of mounting the rubber band on the same.

40 The shell of the gun proper comprises two parts and when placed together and held by suitable means forms the handle 10, the frame portion 11 and the barrel 12. In the top of the barrel 12 and extending the full length thereof is the longitudinal slot 13, the purpose of which will hereinafter be understood. Extending downwardly from this slot 13, communicating with the same and near the end of the barrel are the oppositely arranged notches 14 and 15. Engaging these two notches and the lug 16 on the bottom end of barrel, as shown in Fig. 1 and Fig. 4, is the endless rubber band 17.

45 The projectile to be shot into the air from this gun is made of a single sheet of

material and bent into the form of a toy airplane as shown in Fig. 2. It may be made of any suitable material but preferably light metal or celluloid. Its fuselage 18 is cylindrical and of a diameter somewhat smaller than that of the bore of the barrel. This fuselage extends upward after forming the cylindrical portion and when in the gun upwardly through the longitudinal slot 13 and then outwardly forming the wings 19 and the elevator fins 20. The incidence of the wings and elevators may be bent and changed to cause the airplane to circle, fly straight, zoom, or barrel in the air when shot from the gun.

To shoot the plane from the gun, the tail end of the airplane is inserted in the muzzle end of the barrel and the same is drawn back until the fuselage is completely inside the barrel. By this operation the rubber band which normally rests in the notches 14 and 15 and which was directly in the path of the airplane as it was inserted into the barrel, caught the tail end of the airplane and was thereby unnormally expanded. In other words its tendency will be to contract to normal and in so doing would force the plane from the barrel with great rapidity. To prevent the airplane from leaving the barrel until desired, a trigger member 21 is provided which is rotatably mounted on the rivet 21^a. The upper end of this trigger is designed to engage the notch 22 in the fuselage of the airplane. By pulling the lower portion of the trigger member toward the handle the upper portion will disengage the notch 22 and having no other resistance the rubber band will contract and throw the airplane from the barrel and into the air. To hold the trigger member always in normal position so that the same will automatically engage the notch 22, the rubber band 23 is provided.

All that is necessary is to force the airplane into the barrel until it engages and is held by the trigger member. The gun is then ready to be shot.

When the rubber band 17 breaks from use, another may be readily and easily attached to the gun.

The gun is capable of shooting many kinds of projectiles into the air. If it is desired the projectile may be designed in the form of a dragonfly, grasshopper, or the like.

The gun is very economical to manufacture, the shell being preferably stamped from two pieces of sheet metal.

To prevent the projectile from damaging anything it might come in contact with when shot, a rubber nose 24 is provided.

Some changes may be made in construction and arrangement of my toy airplane projectile gun without departing from the real spirit and purpose of my invention and it is my intention to cover by my claims any modified forms of structure or use of mechanical equivalents which may be reasonably included within their scope.

15 I claim:

1. In a device of the class described, a frame, a handle member, a barrel, a longitudinal slot in said barrel and communicating with its bore, two oppositely arranged notches in said barrel and communicating with said slot, an elastic band normally resting in said notches, a projectile designed to be shot from said barrel, capable of entering said barrel and having a portion extending through said slot.

2. In a device of the class described, a frame, a handle member, a barrel, a longitudinal slot in said barrel and communicating with its bore, two oppositely arranged notches in said barrel and communicating with said slot, an elastic band normally resting in said notches, a projectile designed to be shot from said barrel, and a trigger for releasing said projectile.

3. In a device of the class described, a barrel, a longitudinal slot extending the length of the barrel and communicating with its bore, oppositely arranged notches in said barrel and adjacent the said slot, a lug on

said barrel, and an elastic band engaging 40 said notches and lug, for the purposes stated.

4. In a device of the class described, a barrel, a longitudinal slot extending the length of the barrel and communicating with its bore, oppositely arranged notches in said barrel and adjacent the said slot, a lug on 45 said barrel, an endless rubber band engaging said notches and lug and a toy airplane capable of entering said barrel and stretching said rubber band.

5. In a device of the class described, a frame, a barrel secured to said frame, a longitudinal slot extending the length of the barrel and communicating with its bore, oppositely arranged notches in said barrel and adjacent the said slot, a lug on 55 said barrel, an endless elastic band engaging said notches and lug, a toy projectile capable of entering said barrel and stretching said elastic band, and a rubber nose secured to said projectile.

6. In a device of the class described, a frame, a handle member, a barrel, a longitudinal slot in said barrel and communicating with its bore, two oppositely arranged notches in said barrel, near its muzzle and communicating with said slot, a lug on the under side of said barrel, an elastic band 65 engaging said lug and notches, a toy airplane capable of having its fuselage forced into said barrel to stretch said elastic band and its wings and elevators extending out through said slot, a notch in the bottom of said airplane, a trigger member for holding and releasing said airplane, and a rubber band for yieldingly holding said trigger in 70 normal position, for the purposes stated.

CLAUDE E. MENTZER.
